Primary Examiner — Susan Bennett Hattan*Assistant Examiner* — Suzanne E Tisdell(74) *Attorney, Agent, or Firm* — KPPB LLP(57) **CLAIM**

The ornamental design for a retail fixture, as shown and described.

DESCRIPTION

FIG. 1 is a first isometric view of a retail fixture.

FIG. 2 is a second isometric view of a retail fixture.

FIG. 3 is a front elevational view of a retail fixture.

FIG. 4 is a rear elevational view of a retail fixture.

FIG. 5 is a first side elevational view of a retail fixture.

FIG. 6 is a second side elevational view of a retail fixture.

FIG. 7 is a top elevational view of a retail fixture; and,

FIG. 8 is a bottom elevational view of a retail fixture.

Features shown in broken lines depict environmental subject matter that forms no part of the claimed design.

1 Claim, 4 Drawing Sheets(56)
